(57) **CLAIM**

I claim the ornamental design for a whimsical frog spinner, as shown and described.

DESCRIPTION

FIG. 1 is a front view of my whimsical frog spinner; FIG. 2 is a back view thereof; FIG. 3 is a right side elevational view thereof with the left side elevational view being a mirror image thereof; and, FIG. 4 is a top view thereof. The portions shown in broken lines are for illustrative purposes only, and form no part of the claimed design. The appearance within the unshaded recessed areas of FIG. 1 and the appearance of the unshown connection between the front bow feature and figure form no part of the claimed design.
